UNITED STATES PATENT OFFICE.

JOHN A. McCROHAN, OF NEW HAVEN, CONNECTICUT, ASSIGNOR TO L. CANDEE & COMPANY, OF NEW HAVEN, CONNECTICUT, A CORPORATION OF CONNECTICUT.

CALENDER.

Application filed November 3, 1922. Serial No. 598,704.

To all whom it may concern:

Be it known that I, JOHN A. McCROHAN, a citizen of the United States, residing at New Haven, county of New Haven, and

5 State of Connecticut, have invented a certain new and useful Calender, of which the following is a full, clear, and exact description.

This invention relates to a calender, more 10 particularly, to an engraved roll calender.

In the operation of engraved roll calenders, when it is desired to impress the stock being calendered with a different design, it is necessary to stop the operation of the calender while the engraved roll is being removed and another substituted. The calenders are ordinarily rather large and the rolls 15 quite heavy, while the space in which to operate is usually rather cramped, and as a result, considerable time is taken in making the change. The present invention is an improvement on the calender shown in patent to Clark No. 1,226,949 of May 22, 1917, and in the embodiment of the invention shown it 20 is applied to a calender for making sole stock for rubber overshoes, etc., but it is not however limited in its application to such a calender. In calendering such sole stock it is usually formed with spaced roughened portions 25 corresponding to the heel and ball portion of the sole with an intermediate smooth portion corresponding to the shank on which latter is disposed the brand and any other desired indicia. In larger footwear factories a 30 number of brands of shoes are usually manufactured and in the course of a day's run it becomes necessary to change the engraved roll each time a different brand of sole stock is run. The time occupied in changing a 35 roll amounts to ten minutes or more and it is readily seen that if the roll must be changed a dozen or more times during the day, a large amount of time is taken during 40 which valuable equipment and expensive labor are idle.

An object of my invention is to provide an improved engraved roll calender having an increased capacity.

Another object is to provide a continuously 45 operable changeable roll calender.

Still another object is to provide a calender in which the rolls may be changed with greater facility.

For a detailed description of the invention, reference is had to the accompanying 55 specification and drawings in which latter:

Figure 1 is a front elevation of my improved calender;

Figure 2 is a right-hand elevation of the 60 same with parts omitted;

Figure 3 is a left-hand elevation;

Figure 4 is a detail of an engraved calender roll;

Figure 5 is a detail with parts omitted of 65 a pivoted drive chain bracket; and

Figure 6 is a slide elevation of the bracket.

Referring to the drawings, the numeral 1 designates the base of the machine having the upright side frames 2 and 3. Mounted 70 in the upper part of the side frames are coacting calendering rolls 4 and 5, the roll 4 having fixed journals and the roll 5 having its journals adjustable in the frames 2 and 3 by means of the adjusting screws 6 threaded through the caps 7, which latter are bolted to the frames 2 and 3 in a manner similar to that shown in patent to Clark before mentioned. It will be seen that by actuation of the screws 6, the roll 5 may be adjusted 80 into any desired proximity to the roll 4, and the longitudinal relation of the rolls may also be varied, that is, the rolls may be spaced more closely at one side than at the other, so as to produce a calendered sheet of greater thickness at one edge than at the other. Below the rolls 4 and 5 a second pair of rolls 8 and 9 are mounted in the frames 2 and 3 85 in a similar manner, the roll 8 being fixed while the roll 9 is adjusted by means of the screws 10 threaded in the caps 11. Below the rolls 8 and 9 is a roll 12 fixedly mounted in the side frames 2 and 3, and adapted to cooperate with the roll 12 on each side thereof, are engraved rolls 13 and 14. Each of 90 these engraved rolls is mounted in the same manner in the frames 2 and 3 and a description of one will therefore suffice. The roll 13 is carried in split bearings 15 movable in recesses in the frames 2 and 3, each bearing 100 having a handle 16 projecting therefrom, against which bears an adjusting screw 17 threaded through a cap 18. The caps 18 are not mounted in the same manner as caps 7 and 11 but are hingedly connected to the 105 respective frames 2 and 3 at 19. A bolt

20 projecting from each frame passes through the upper slotted end of a corresponding cap 18 and the cap is held in closed position by a nut 21. When it is desired to 5 remove the roll 13 or 14 the nuts 21 are unscrewed and the caps 18 allowed to drop to a horizontal position, in which position they are held by the stop shoulder 22 of each cap engaging a corresponding shoulder 23 on the 10 frame. It will thus be seen that the horizontally disposed caps form a support or table on which the bearings 15 and roll 13 may be slid when it is desired to remove the roll.

15 At the end of the shaft 24 of the roll 8 which projects through the frame 3 a main drive sprocket 25 is mounted on which is disposed a drive chain 26 connected to any suitable source of power. Also mounted on 20 the same end of the shaft 24 is a second sprocket 27, which through the chain 28 drives the sprocket 29 on the shaft 30 of roll 5, the chain also passing over the idler sprockets 31 and 32 carried on frame 3. It 25 will be seen that by this construction the roll 5 is driven in a direction opposite to that of the roll 8. Secured at the end of the shaft 30 of roll 5 which is adjacent the frame 2 is a sprocket 33, which by means of the chain 34 drives a sprocket 35 on the shaft 36 of roll 9 (see Fig. 3). Secured at the end of shaft 24 of roll 8 which is adjacent the frame 2 is a sprocket 37, which by means of the chain 38 drives a sprocket 39 on shaft 40 of roll 35 4, the chain also passing over an idler sprocket 41 secured to the frame 2. Adjacent the sprocket 27 a sprocket 42 is secured on the shaft 24 of roll 8 and this sprocket by means of chain 43 drives a sprocket carried 40 by the clutch member 44, which latter is loosely mounted on the shaft 45 of roll 12 (Figs. 1 and 2). A sprocket 46 is mounted on the shaft 36 of roll 9 and by means of chain 47 drives a sprocket carried by a second clutch member 48, also loosely mounted on the shaft 45, the chain 47 also passing over an idler sprocket 49 carried by the frame 3. A clutch member 50 is slidably keyed on the shaft 45 between the clutch 50 members 44 and 48 and may be moved into driving relation with either of them by means of the operating lever 51 fulcrumed at 52 on the frame. The lower end of lever 51 is pinned to screw block 53 carried by the threaded end of a shaft 54, the other end of the shaft having a gear 55 meshing with a gear 56, which latter in turn is mounted on a short shaft, having at its other end a gear 57, meshing with gear 58 on shaft 59. 55 The shaft 59 is connected at each end by universal joints 60 with the angularly disposed shafts 61 having the hand wheels 62 disposed at opposite sides of the machine. The shaft 63 of engraved roll 13 carries at 65 its end adjacent the frame 2 a sprocket 64, and in a similar manner the shaft 65 of roll 14 carries a sprocket 66. Secured to the frame 2 is a bracket plate 67 having projecting therefrom a bearing sleeve 68 slightly spaced from the shaft 45 of roll 12, and 70 pivotally mounted on this sleeve is a rocking chain carrying bracket 69 (Figs. 3, 5 and 6). Mounted on opposite ends of the bracket are idler sprockets 70 and 71 over which passes a chain 72, the latter being driven by a sprocket 73 mounted on shaft 45 of roll 12. Carried by the lower end of bracket 69 is a curved segmental rack 74 adapted to be actuated by a worm 75 on shaft 75 59. It will be seen from the above construction that the roll 12 may be rotated in either direction depending on whether it is connected in driving relation to the roll 8 or 9 by the manipulation of the hand wheels 62. It will also be seen that by reason of the connection of the chain bracket 69 with the worm 75, the chain 72 will be operatively connected to either the sprocket 64 or the sprocket 66, depending on the direction in which the hand wheels 62 are rotated. In 80 order to prevent too great a pivotal movement of the bracket 69 with consequent excessive tension on the chain 72, the bracket is provided with the stop shoulders 76 which are adapted to engage one or the other of the adjustable stop screws 77 carried by the bracket plate 67.

85 Between the upper two pairs of calender rolls a tension roll 78 is disposed and between the middle pair and lower rolls a second tension roll 79 is disposed. A presser bar 80 is disposed between the rolls 8 and 9 in order to provide pressure on the stock and to facilitate feeding the same, and similar presser bars 81 and 82 are disposed between 90 the roll 12 and the respective engraved rolls 13 and 14.

95 Between the upper two pairs of calender rolls a tension roll 78 is disposed and between the middle pair and lower rolls a second tension roll 79 is disposed. A presser bar 80 is disposed between the rolls 8 and 9 in order to provide pressure on the stock and to facilitate feeding the same, and similar presser bars 81 and 82 are disposed between 100 the roll 12 and the respective engraved rolls 13 and 14.

105 In Figures 1 and 4 is shown a common form of engraved roll in use for calendering sole stock. In this roll there is provided a roughened portion 83 integral with the roll, an intermediate removable ring 84 provided with brand designations 85 or other indicia as shown in Figure 1, and a second roughened portion which is carried by a removable ring 86. The rings 84 and 86 are keyed to the shaft of the roll and are held in position by a threaded lock nut 87. In the calendered stock that part formed by the roughened portion 83 corresponds to the 110 ball part of a sole, the smooth part formed by the ring 84 corresponds to the shank of the sole, while the part formed by the roughened portion of ring 86 corresponds to the heel of the sole. It will be seen that in addition to the time taken in removing such a roll from the calender additional time is required to change the ring carrying the brand mark 85.

115 In operation the stock 88 is let down be- 120

125 130

In operation the stock 88 is let down be- 130

tween the upper pair of rolls 4 and 5, then around the tension roll 78, through the bank of stock formed by the rolls 8 and 9, and in the instance shown by a dot and dash line in Figure 3 is then led around the left-hand side of the tension roll 79 and down through the bank formed by the roll 12 and engraved roll 14, the finished stock passing under the roll 14 and up onto the conveyor 89. When the machine is operating in this manner the roll 12 is driven in a clockwise direction (Fig. 3) from the roll 8, the clutch member 50 being at this time connected to the clutch member 44, as shown in Fig. 1. At the same time, by reason of the movement of worm 75, the chain bracket 69 has been moved to the right (Fig. 3) to place the engraved roll 14 in driving relation with the sprocket 73 on roll 12. When the desired batch of stock has been run having one brand impressed thereon and it becomes necessary to change to another brand, the machine is run very slowly, the stock cut above tension roll 79 and the hand wheel 62 operated to release the clutch member 50 from clutch member 44 and engage it with clutch member 48, thereby reversing the direction of roll 12 and driving it in a counter clockwise direction. At the same time the movement of the worm 75 shifts the chain carrying bracket 69 to free the roll 14 from driving relation with roll 12 and engage roll 13 instead. The cut stock end is then pulled over to the right-hand side of tension roll 79, led down between the rolls 12 and 13, up over the idler roll 90, under the idler roll 91 and onto the second conveyor 92 in the manner shown by dash lines in Figure 3.

After shifting to place the engraved roll 13 in operation, the roll 14 may then be removed at leisure without in any way interfering with the operation of the calender. As before pointed out the caps 18 are unbolted and swung down into their horizontal position as shown in Figure 2, the handles 16 of journals 15 grasped and the roll 14 drawn out onto the caps 18 where it may be readily lifted by an overhead crane or in any other manner and another roll having a different brand marked thereon substituted. The handles 16 form a convenient means for withdrawing the journals and the roll and also prevent burning of the hands of the operator by reason of heated journals.

It will be seen that by my invention an engraved roll calender of greater capacity has been devised, which can be operated continuously for calendering differently impressed stocks, and in which the engraved roll can be removed with greater facility when it is desired to change the same.

While a specific embodiment of the invention has been shown and described, it

is obvious that numerous changes may be made in the details, and it is not limited in its use to the particular purpose set forth.

Having thus described my invention, what I claim and desire to protect by Letters Patent is:

1. In a calendering machine, a plurality of adjacent calendering rolls, drive means therefor, and means for at will shifting certain of said rolls into and out of connection with said drive means. 75

2. In a calendering machine, a series of adjacent calender rolls, drive means therefor, and means for selectively connecting any two adjoining rolls to said drive means. 80

3. In a calendering machine, a series of adjacent calender rolls, drive means therefor, and means for selectively connecting any two adjoining rolls to said drive means while maintaining the direction of feed 85 through the rolls constant.

4. In a calendering machine, a plurality of calender rolls including means for impressing a predetermined design on the stock passing therethrough, and means for varying said design without stopping the machine. 90

5. In a calendering machine, a calender roll, a pair of calender rolls adjacent thereto, drive means for said first roll, and means for alternatively connecting each of said pair of rolls with said drive means. 95

6. In a calendering machine, a calender roll, a pair of calender rolls adjacent thereto, reversible drive means for said first roll, and means for alternatively connecting each of said pair of rolls to said drive means and simultaneously reversing said first roll. 100

7. In a calendering machine, a calender roll, a pair of removable calender rolls adjacent thereto, reversible drive means for said first roll, and means whereby either of said pair of rolls may be driven from the first roll while the other is being removed 110 and exchanged.

8. In a calendering machine, a pair of cooperating calender rolls, a third calender roll, means for driving it from either of said first rolls, a pair of engraved calender 115 rolls on either side of said third roll, and means for driving either of said engraved rolls from said third roll.

9. In a calendering machine, a pair of cooperating calender rolls, a third calender 120 roll, a pair of engraved calender rolls on either side of said third roll, and means connected to said first pair of rolls for at will driving said third roll in either direction and either of said engraved rolls in co-operating relation therewith. 125

10. In a calendering machine, a pair of cooperating calender rolls, a third roll, means for driving said third roll from either of said pair, a pair of engraved rolls 130

cooperating with said third roll, a floating chain drive mechanism actuated from said third roll, and means for operatively connecting said drive mechanism to either of 5 said engraved rolls.

11. In a calendering machine a pair of oppositely driven calender rolls, a third roll, clutch mechanism for driving said third roll from either of said pair, a pair of engraved rolls cooperating with said third roll, a floating chain drive mechanism actuated from said third roll, and means actuated in unison with said clutch mechanism for operatively connecting said chain drive 10 mechanism to either of said engraved rolls. 15

12. In a calendering machine, a reversibly driven calender roll, a pair of engraved rolls adjacent thereto, means for driving either of said engraved rolls, governing 20 means operable from different points on the machine, and means connected to said governing means for reversing the direction of said first roll and connecting one of said engraved rolls to said driving means.

13. In a calendering machine, a removable calender roll, means for retaining it in operative position, and means whereby said last means may be horizontally disposed to receive the roll in removing the latter. 25

14. In a calendering machine, a frame, a removable calender roll mounted therein, hinged retaining plates having threadedly connected thereto adjusting screws for holding the roll in position, means for holding the plates in closed position, and stop means for holding the plates horizontally when in open position. 30 35

15. In a calendering machine, a frame, a journal movable therein and having a handle, a calender roll carried by said journal, a retaining plate secured to said frame, and an adjusting screw threaded in said plate and engageable with said handle. 40

Signed at New Haven, county of New Haven, and State of Connecticut, this 31st 45 day of October, 1922.

JOHN A. McCROHAN.
